BEVERAGE DISPENSER

Gordon W. Florian, Bridgeport, Conn., assignor to The Nicholas Company, Hartford, Conn., a corporation of Connecticut

Application January 7, 1949, Serial No. 109

Term of patent 3½ years

(Cl. D2—3)

To all whom it may concern:

Be it known that I, Gordon W. Florian, a citizen of the United States, residing at Bridgeport, in the county of Fairfield and State of Connecticut, have invented a new, original, and ornamental Design for Beverage Dispenser, of which the following is a specification, reference being had to the accompanying drawing, forming part thereof.

Figure 1 is a view in perspective showing the front, one side and top of a beverage dispenser, embodying my new design; and

Fig. 2 is a view in perspective showing the rear, the other side and the top of my new beverage dispenser.

I claim:
The ornamental design for a beverage dispenser, as shown.

GORDON W. FLORIAN.
